TOOTHBRUSH AND DENTIFRICE PACK

James Francis Waters, New York, N. Y.

Application July 24, 1948, Serial No. 40,573

9 Claims. (Cl. 132—84)

1

This invention relates to devices for dispensing dentifrice. Among the objects of the invention is to provide a package and a dentifrice-dispensing device which are so associated as to conserve the contents of the dispensing device and yet provide for ready accessibility to the dentifrice for application to a tooth brush. The invention comprises a receptacle which is adapted for convenience in housing a dentifrice-containing device and a tooth brush for the use of travellers as well as for home use. The receptacle provides a chamber for receiving and storing the dentifrice-dispensing device, a chamber through which access may be had to the dentifrice contained in the dispensing device, and a third chamber for containing a tooth brush. A removable wall or cover-plate normally separates the dentifrice-dispensing device from the chamber through which access is had to the dentifrice and serves to preserve the dentifrice in a fresh condition.

The dentifrice-dispensing device is in the form of an elongated box with a moveable wall which is perforated so that dentifrice passing through the holes in the wall becomes available to a brush for dental use. As the dentifrice is consumed by repeated usage, the moveable wall is sustained by the dentifrice remaining within the box. It is a purpose of the invention to provide a package or receptacle which is constructed and arranged so that it can be replenished with filled dentifrice-dispensing devices when the dentifrice in an original device is consumed.

Referring to the accompanying drawings:

Fig. 1 illustrates a package or receptacle, a dentifrice-dispensing device and a moveable wall or cover for preserving the dentifrice, and a collapsible tooth brush;

Fig. 2 is a bottom view of the receptacle;

Fig. 3 is a longitudinal section through the receptacle;

Fig. 4 is a view of the open end of the receptacle on line 4—4 of Fig. 3;

Fig. 5 illustrates a manner by which the dentifrice may be applied to a tooth brush;

Fig. 6 is a plan view, partly in section, of the dispensing device;

Fig. 7 is a bottom view of the dispensing device;

Fig. 8 is a longitudinal section of a modified form of dispensing device;

Fig. 9 is a view of the dispensing device illustrated in Fig. 8, as wrapped in a protective covering;

2

Fig. 10 is a sectional view of a modified form of a receptacle;

Fig. 11 is a side view of a tooth brush with a collapsible handle;

Fig. 12 is a back view of the brush;

Fig. 13 is a section on line 13—13 of Fig. 12, and

Fig. 14 is a detail showing the joint of the brush handle in coupled relationship.

10 The package of the present invention includes a receptacle in the form of a casing 10 which, together with a removable cover 11, forms a convenient carrier for always maintaining the dental hygiene devices assembled for ready use. The casing, as well as the other dental aids, including the dentifrice-dispensing device 12 and all of its component parts and the removable wall or closure 13, which serves to prevent the drying out of the dentifrice, are preferably made from a synthetic organic plastic, but may be formed of metal or other suitable materials.

25 The interior of the casing is divided into a plurality of chambers, of which chamber 14 is for containing the dentifrice-dispensing device 12, the chamber 15 is for accommodating a tooth brush when access to the dentifrice contained in the dentifrice-dispensing device is desired, and a chamber 16 is for storing or containing one or more tooth brushes. These chambers are all open at one end of the casing 10 and are closeable by the single cover 11.

30 The chamber 14 is of sufficient proportions to accommodate the dentifrice-dispensing device 12 and the removable wall 13. It includes a lower wall 17 which separates the dentifrice-dispensing device 12 from the chamber 16. The upper limit of chamber 14 is determined by a pair of flanges 19 and 20 projecting inwardly of the side walls of the casing 10 and the removable wall 13.

35 The portions of the walls of the casing 10 which enclose the chamber 16 are provided with holes 21, 22, 23, 24, 25, etc. in the bottom wall 26 of the casing and with holes 27, 28, 29, etc. in both 40 of the side walls of the casing in order to provide ventilation for the tooth brush, Figs. 1 and 2.

45 The container of the dentifrice-dispensing device 12 is in the form of an open ended container or box 30, rectangular in section, and having such length as to be accommodated within the chamber 14 of the casing 10. It includes a bottom wall 31, an end wall 32, and parallel side walls 33 and 34, as illustrated in Figs. 3—7. The bottom wall 31 is provided with a filling opening 50 34' into which the neck of a tooth paste tube may

be inserted for replenishing the dentifrice 35. A cover 36 is supported by a pin 37, about which the cover may be swiveled for closing and opening the opening 34'.

The upper wall of the box 30 comprises a flange 38 which projects interiorly from the side and end walls of the box, and a moveable wall or plate 39 which has a plurality of perforations 40, 41, 42, etc. through which the dentifrice paste is exuded when the wall is subjected to pressure. The perforations in the moveable wall are in sufficient number to aggregate a relatively large open area while at the same time leaving sufficient solid wall to restrain the free flow of dentifrice from the box, Figs. 3, 5, 6. Each of the openings 40, 41, etc. is of sufficient size to provide enough dentifrice for an individual application of paste when a brush is passed over the same a few times.

In order that the dentifrice may be used equally throughout the area of the box, it is desirable that the moveable wall 39 be maintained parallel to itself as it descends within the box. This is accomplished by making the moveable wall 39 from a relatively thick sheet of material and by forming its longitudinal side edges with surfaces in planes normal to the perforated surface of the wall. The wall 39 has an area but slightly less than the horizontal inside area of the box and is therefore maintained perpendicular to the side walls.

The open end of the box 30 is normally closed by a sliding gate 45 whose upper and lower edges fit in grooves 46 and 47 of the box, Fig. 3. This gate retains the perforated partition 39 within the box. The slide extends from one side of the box as shown at 48, Fig. 6.

In order to insert the box into chamber 14 it is first necessary to remove the gate 45. The surface of the wall of the casing 10 has an undercut 48' to enable fingernail engagement with a slot in the end 48 of the gate 45 so that the gate may be withdrawn. After the box has been inserted in chamber 14, the gate 45 is inserted through an opening 49 in the side wall of the casing 10 and is engaged in the upper and lower grooves 46 and 47 of the box. The engagement of the slide with the opening in the wall of the casing locks the box within the casing.

When the box 30 is in place within the casing 10, access to the dentifrice may be had through chamber 15, but when the device is not in use, it is desirable to prevent access of air to the dentifrice, in order to prevent evaporation. This is accomplished by the use of the removable wall or partition 13, which is slid into place between the under surfaces of flanges 19 and 20 and the flange 38 of the box, as illustrated in Figs. 3 and 4. The partition 13 is provided with a finger piece 49' by which it may be manipulated.

The box 50 of the dentifrice-dispensing device illustrated in Figs. 8 and 9 is similar to the one previously described, except that the lower or bottom wall 51 is not provided with an opening for receiving a tooth paste tube. This box is suitable for sale as a supplemental unit for replacement of the dispensing device originally forming a part of the package. The box is provided with a covering of an air-tight film 52, such as cellophane, which is suitable for containing the paste and preventing its evaporation. As thus wrapped this unit does not require a slidable gate at the open end of the box. When the unit is to be used it is necessary only to remove the wrapping, insert the box in chamber 14 and then slide the gate 45

through the opening 49 in the wall of the casing to lock the box in place within the casing 10.

The casing may be made in any length desired, either to accommodate a tooth brush of standard size, or a tooth brush which has a collapsible handle. The tooth brush illustrated in the drawings includes a brush portion having a shank 53 and a handle portion 54 which are adapted to be connected by a joint member 55. The joint member is provided at its ends with studs 56 and 57 which are adapted snugly to engage within the socket 58 of the shank 53 and within the socket 59 of the handle 54, respectively, as illustrated in Figs. 12 and 14. The joint member is provided with slots 60 and 61 through which pins 62 and 63 extend. Pin 62 is carried by the shank 53 and pin 63 is carried by the handle 54.

For extending the handle in line with the shank, the shank, the joint member and handle are disposed in axial alignment as shown in Fig. 13 and then frictionally engaged by forcing the members together as illustrated in Fig. 14. As thus constituted the handle is rigid and a tooth brush of standard length is had.

The case illustrated in Fig. 10 is similar to the casing previously described except for the absence of a dividing wall between the dentifrice-containing chamber 64 and the tooth brush chamber 65. Intermediate these two chambers is a pair of rails 66, 67, which serve to support the removable box 50 in which the dentifrice is contained.

What is claimed is:

1. A dentifrice-dispensing device comprising a container for dentifrice and having an elongated opening at one face thereof, a moveable plate within said container, said plate closing said opening and containing a plurality of holes for the passage of dentifrice therethrough, a casing having an opening for the insertion of said container into said casing; means within said casing for locating said container within a portion of said casing, a closure for said container, said closure being adapted for covering the elongated opening in said container and for removal from said casing to permit access to the holes in said moveable plate.

2. A dentifrice-dispensing device comprising a container for dentifrice and having an elongated opening at one face thereof, a moveable plate within said container, said plate closing said opening and containing a plurality of holes for the passage of dentifrice therethrough, a casing having an opening for the insertion of said container into said casing; a chamber within said casing for receiving said container, said container having a removable wall at one end which engages a slot in the wall of said casing to lock said container within the casing, and a removable closure for covering the elongated opening in said container.

3. A dentifrice-dispensing device comprising a container for dentifrice and having an elongated opening at one face thereof, a moveable plate within said container, said plate closing said opening and containing a plurality of holes for the passage of dentifrice therethrough, a casing having an opening for the insertion of said container into said casing, means for dividing said casing into three chambers including a central chamber for receiving said dentifrice container, a second chamber communicable with said central chamber through an opening and in which a tooth brush may be inserted for passage over said perforated plate for applying dentifrice to

the tooth brush, and a third chamber for storing a toothbrush, each of said chambers being accessible from outside of said casing through said opening in said casing.

4. A dentifrice-dispensing device comprising a container for dentifrice and having an elongated opening at one face thereof, a moveable plate within said container, said plate closing said opening and containing a plurality of holes for the passage of dentifrice therethrough, a casing having an opening for the insertion of said container into said casing, means for dividing said casing into three chambers including a central chamber for receiving said dentifrice container, a second chamber communicable with said central chamber through an opening and in which a tooth brush may be inserted for passage over said perforated plate for applying dentifrice to the tooth brush, a third chamber for storing a tooth brush, each of said chambers having an opening through a wall of said casing for gaining access to said chambers, and a removable partition supported in said casing between said first and second chambers and in contacting relation with the open face of said container for preventing the evaporation of the dentifrice contained within said container.

5. A dentifrice-dispensing device comprising a casing, a container for dentifrice, means separating said casing into three chambers including an intermediate chamber for receiving said dentifrice container, said chambers having open ends adapted to be covered by a cover, said container having a perforated wall through which dentifrice within the container is exuded, a removable partition for separating said intermediate chamber from an adjacent chamber which, upon removal from the casing, provides access to the perforated wall of said container from that adjacent chamber, and a cover for said casing whereby the open ends of each of said chambers are covered.

6. A dentifrice-dispensing device comprising a container for containing dentifrice, said container having opposite parallel walls, a bottom wall, an end wall, an open end, and an open face opposite said bottom wall, a perforated plate closing said open face and adapted to be guided for movement within said container in a direction parallel to said parallel walls and towards and away from said open face, said plate having holes therein for permitting the passage of dentifrice therethrough, and a removable gate for closing said open end of said container.

7. A dentifrice-dispensing device comprising a container for containing dentifrice, said container having opposite parallel walls, a bottom

wall, an end wall, an open end, and an open face, a perforated plate closing said open face and adapted to be guided for movement within said container in a direction parallel to said parallel walls and towards and away from said open face, said plate having holes therein for permitting the passage of dentifrice therethrough, and a removable gate for closing said open end of said container, said container having an opening in a wall thereof for enabling the introduction of a paste dentifrice to said container.

8. A dentifrice-dispensing device comprising a rectangular box for containing dentifrice, said box having substantially parallel side walls, a bottom wall, an end wall, a removable wall for closing an open end of said box, and an open face bordered by flanges extending inwardly from said parallel walls, a moveable upper wall in the form of a plate for closing said open face, said plate being adapted to be guided by opposite side walls of the container for movement parallel to the plane of its surface and towards and away from said flanges, said plate having a plurality of holes therein for exuding dentifrice from the box when pressure is applied to said plate.

9. A dental aid comprising a casing with a removable cover, a dentifrice-dispensing device, said device including a box containing a dental paste and having a perforated wall for exuding paste therethrough, a closure for said perforated wall, a chamber in the casing for containing said dentifrice-dispensing device and said closure, a second chamber in said casing, said second chamber having an opening communicating with said first chamber for gaining access to said perforated wall of said box, and a third chamber for receiving a tooth brush, each of said chambers having an opening normally covered by said cover.
